R. I. EDWARDS

CORNER BEAD CLAMP

Filed Sept. 27, 1920

By Whittlemon, Hulland & Whittlemon

Attorneys

UNITED STATES PATENT OFFICE.

ROBERT I. EDWARDS, OF DETROIT, MICHIGAN.

CORNER-BEAD CLAMP.

Application filed September 27, 1920. Serial No. 413,118.

To all whom it may concern:

Be it known that I, ROBERT I. EDWARDS, a citizen of the United States of America, residing at Detroit, in the county of Wayne

5 and State of Michigan, have invented certain new and useful Improvements in Corner-Bead Clamps, of which the following is a specification, reference being had therein to the accompanying drawings.

10 The invention relates to corner bead clamps designed for the use of plasterers in the proper positioning and holding of said beads until the plaster is set. It is the object of the invention to provide a temporary clamp which may be quickly positioned and which will securely hold the bead properly aligned while the plaster is being laid and subsequent thereto until it is completely hardened. The clamp may then be removed

15 and can be used again for other work. The invention therefore consists in the construction as hereinafter set forth.

In the drawings:

Figure 1 is a side elevation of a brick wall 25 showing the corner bead secured thereto by my improved clamp;

Figure 2 is a horizontal section thereof;

Figure 3 is a perspective view of the clamp;

30 Figure 4 is a perspective view of one construction of corner bead;

Figure 5 is a similar view of a modified construction of corner bead;

Figure 6 is a view similar to Figure 2, 35 showing a modified construction of clamp.

In plaster finish where there is a projecting corner, it is necessary to reinforce the same to prevent breaking of the plaster. One method commonly used is the employment

40 of a metallic bead which extends along the angle of the wall and is embedded in the plaster, so as to be concealed thereby but to nevertheless reinforce the same. In placing these beads it is essential that they should

45 be lined up with the finish surfaces, so as to neither project therebeyond nor to be so deeply embedded as to fail in reinforcement. If, however, this beading is placed by the lather or by the carpenter, it is difficult to

50 properly align the same, for the exact plane of the finish surface may not be fully determined. With my improved construction the reinforcing bead may be placed by the plasterer after the work has progressed sufficiently to fully determine the planes of the

intersecting surfaces. Also the construction is such that it can be quickly applied and when the work is completed, as quickly removed.

In detail, A is a wall, such, for instance, 60 as a brick wall, which is to be plastered, and B is a projecting corner. C is the corner bead for reinforcing the plaster at the corner. D is my improved clamp which comprises a pair of hinged jaw members D' and 65 D² suitably fashioned at D³ and D⁴ for engaging the bead. As shown in Figure 2, these members have shanks E and E' which extend at right angles to each other and which are preferably connected with extension strips of wood F and F'. One or more surfaces of the clamp, preferably the inner surface of the shanks E and E', and the extension members F and F' thereof extend 70 in the plane of the finished surface of the plaster when the bead is properly positioned for embedding therein. Therefore, in the setting of the clamp it is only necessary to secure the same to the wall by nails or otherwise with this surface properly positioned. The work may be facilitated by first 75 plastering the wall, or a portion thereof, adjacent to the corner and then setting the clamp so that the inner faces referred to will lie flush with this plastered section. After 80 the clamps are secured, the work of plastering may be continued up to the corner embedding the bead and when the plaster has hardened, the clamps are removed.

With the construction shown in Figure 6, 90 instead of securing the clamp by members engaging the angling surfaces of the wall, the clamp is secured by engagement with one of the surfaces, which permits of applying the bead to a corner but slightly projecting. With this construction the co-operating jaw members G and G' which clamp the bead at G² and G³ respectively are slidably engaged with each other and are clamped by a cam lever H, pivoted at I. 95 The clamps may be secured in position in the same manner as before described, only that there is but one shank, which, however, is laid with its inner face flush with the inner surface of the wall.

100 What I claim as my invention is:

1. A bead clamp comprising means for gripping the bead, and including a securing shank having the inner surface thereof adapted to be positioned in predetermined 110

relation with the finish surface of the wall when the bead is properly positioned at the corner thereof.

2. A bead clamp comprising means for gripping the bead, and including a securing shank having the inner surface thereof adapted to be positioned in alignment with the finish surface of the wall when the bead is properly positioned at the corner thereof.
5. A bead clamp comprising means for gripping the bead, and including a securing shank having the inner surface thereof adapted to be positioned in alignment with the finish surface of the wall when the bead is properly positioned at the corner thereof.
10. A bead clamp comprising relatively movable jaws for gripping the bead, and including a securing shank extending from one of said jaws and having the inner surface thereof adapted to be positioned in alignment with the finish surface of the wall when the bead is properly positioned at the corner thereof.
15. A bead clamp comprising a pair of pivoted jaws for gripping the bead, and including a securing shank extending from one of said jaws and having the inner surface thereof adapted to be positioned in alignment with the finish surface of the wall when the bead is properly positioned at the corner thereof.
20. A bead clamp comprising a pair of clamping jaws for gripping the bead, and including a securing shank extending from one of said jaws and having the inner surface thereof adapted to be positioned in alignment with the finish surface of the wall when the bead is properly positioned at the corner thereof.
25. A bead clamp comprising means for

gripping the bead and including a securing shank having the inner surface thereof adapted to be positioned in alignment with the finish surface of the wall when the bead is properly positioned at the corner thereof, and means for temporarily securing said shank to the wall.

30. A bead clamp comprising a pair of pivoted jaws for gripping the bead and shanks respectively extending from said jaws and having the inner surface of one of said shanks adapted to be positioned in alignment with the finished surface of the wall when the bead is properly positioned at the corner thereof.

35. A bead clamp comprising a pair of pivoted jaws for gripping the bead and shanks respectively extending from said jaws, said shanks being disposed in planes 45 at right angles to one another and having their inner surfaces adapted to be arranged in alignment with the finish surface of the wall when the bead is properly positioned at the corner thereof.

40. In testimony whereof I affix my signature.
50. ROBERT I. EDWARDS.
